DESIGN FOR A TEXTILE FABRIC

James Howard Hoffman, New York, N. Y.

Application July 2, 1937, Serial No. 70,217

Term of patent 3½ years

To all whom it may concern:

Be it known that I, James Howard Hoffman, a citizen of the United States and a resident of the city, county, and State of New York, have invented a new, original, and ornamental Design for a Textile Fabric, of which the following is a specification, reference being had to the accompanying drawing, forming part thereof.

The figure is a plan view of the textile fabric, showing my new design.

I claim:

The ornamental design for a textile fabric as shown.

J. HOWARD HOFFMAN.
